GUARD RAIL

Douglas P. Steward, Johnstown, Pa.

Application December 6, 1932, Serial No. 646,011

5 Claims. (Cl. 238—20)

This invention aims to provide a guard rail of simple design, which will be relatively inexpensive to manufacture, but fully as strong and efficient as any of the types heretofore available. 5 The guard rail of the invention and its mode of manufacture possesses sufficient flexibility to allow it to conform, as far as general details and alignment are concerned, to various steam railroad and street railway requirements. One object of the invention is to provide a guard rail 10 of two separately formed parts, so that the guard rail proper can be fabricated from material having a greater resistance to wear than the supporting part of the guard structure. This is 15 advantageous, for it provides a construction wherein the part subjected to severest service can be made of relatively high grade material, such as high carbon heat treated steel or the like and the remainder of the structure can be 20 made of various grades of low carbon steel or the like.

A further object of the invention is to provide a guard rail structure comprised of a base portion having integrally formed chairs with recessed seats adapted to support with great rigidity a separately formed guard rail. Another 25 more detailed object of the invention relates to the provision of a guard rail constituting two 30 separately formed parts, one of which has a base portion adapted to support the running rail and integral chairs, the other of which constitutes the guard rail proper, which is notched for interlocking engagement with the chair portions of the base.

The above and other features of the invention 35 will be more fully apparent from the following detailed disclosure when read in connection with the accompanying drawings, in which—

Fig. 1 is a plan view showing my improved 40 guard rail and a related running rail;

Fig. 2 is a detail view in side elevation showing the guard rail structure alone;

Fig. 3 is an elevation viewed from the left end 45 of Fig. 1;

Fig. 4 is a transverse vertical section on line 4—4 of Fig. 1;

Fig. 5 is a view illustrating a modification; 50 Fig. 6 is a perspective detail of the guard rail.

Referring in detail to the drawings, 1 designates the guard rail and 2 the supporting base 55 thereof. This base is provided with upstanding chair portions, indicated generally by numeral 3. Each chair portion includes upwardly extending parts 4 and 5, which define the upright boundaries of recessed seats 6, in which the

guard rail is adapted to be fitted. On one face, the guard rail is formed with diverging notches 7, which are adapted for interengagement with the projections 5 of the chairs. On the opposite face, the guard rail is formed with notches 8 into which the projection 4 of the chairs extend. The notches 8 are substantially parallel, whereas the notches 7 are other than parallel. In Fig. 2, the notches 7 are shown as converging upwardly. Alternatively, these notches may be formed to converge downwardly, as illustrated in the modification of Fig. 5. The extensions 4 and 5 of the chair portions, as formed in the process of manufacture, are all substantially parallel. At the time of assembly a heavy pressure is applied 10 to the guard rail, which results in bending the extensions 5 to the diverging positions, such as shown in Figs. 2 and 5, thus mechanically interlocking the notched guard rail 1 with the chair portions. If desired, however, I also contemplate merely seating the substantially rectangular guard rail within squared recesses 6 formed in the chair portions and then welding the guard rail to the chair extensions 4 and 5. Or, in some cases, I may provide the interlocking notched 15 arrangement above described and also weld the guard rail to the chair portions at one or more points.

The base 2 of the structure has a bearing portion 9, which extends laterally a sufficient distance to extend under the flanges 10 of the running rail 11. This base is provided with suitable spike holes 12 by means of which the same can be spiked to the usual railway ties. 20

At each end, the guard rail may be beveled as 25 indicated at 13. Adjacent these beveled portions, the end chair portions 14 may be bent over at an angle, as clearly indicated in Figs. 1 and 2.

The guard rail can be conveniently made of 30 square or rectangular bar stock and it can be bent in plan to the shape indicated in Fig. 1, wherein it is noted that the intermediate portion is substantially or approximately parallel 35 to the running rail 11, while the opposite ends are flared away from the rail. The guard rail 40 will generally be made of high carbon treated steel. This material has a substantially greater 45 resistance to wear than that of the base and chair portion. Such a composite structure enables me to use relatively inexpensive steel for 50 those portions not subjected to wear and provides an adequate wear resistant guard for that 55 part of the structure which in service receives the severest wear because of contact with the

wheel flanges or other moving parts of the rolling stock.

The base and chair portion of the guard rail structure herein described may be formed of relatively inexpensive low carbon steel. Usually, this part of the structure will be stamped out from flat material and bent to final form on suitable presses, or the base and chair portions may be integrally formed by drop-forging. Or, alternatively, they may be otherwise forged. I also contemplate casting the base and chair portions and securing the heat treated steel guard rail in place, by interlocking slotted parts or by welding.

The guard rail, instead of being made of high carbon heat treated steel, may alternatively be made of wear-resisting alloy steels such as high manganese chrome nickel, steel, etc.

Instead of cutting or stamping out the flat stock to form the base and chair portions, such stock can be fashioned by burning the same along suitable outlines by an oxy-acetylene torch. Such burning avoids the use of expensive dies which are necessary when the parts are stamped out.

While I have described quite precisely the detailed structural features of the embodiment of the invention herein illustrated it is not to be construed that I am limited thereto since various modifications and substitutions of equivalents may be made by those skilled in the art without departure from the invention as defined in the appended claims.

What I claim is:—

1. A railway track adjunct comprising a base, a plurality of chairs forming an integral part thereof, each chair comprising two upwardly extending portions whose upper extremities converge with respect to one another, seats formed in said converging extremities and a guard rail having a side wall with converging notches formed therewith for engagement with said upwardly extending extremities of the chairs.

2. A railway track adjunct comprising two separately formed parts, namely, a base plate having upwardly bent laterally extending chair portions intermediate the ends of the plate, recessed seats in the chair portions, a guard rail held in said seats and interlocked with said chair portions, and upwardly bent end plates in alignment with and abutting the ends of the guard rail. 5

3. A railway track adjunct comprising two separately formed parts, namely, a base formed of flat plate stock of substantially uniform thickness throughout adapted to span the spaces between several adjacent ties, chair portions bent upwardly and extending laterally from said base, upwardly opening recessed seats in said chair portions, a guard rail having substantially upright notches in interlocking engagement with the chair portions and end plates in alignment with and abutting the ends of the guard rail. 10

4. A railway track adjunct comprising a base, 20 a plurality of chairs forming an integral part thereof, each chair comprising two substantially upright converging portions, seats formed in said converging portions, a guard rail having a side wall with converging notches formed therein for 25 interlocking engagement with said chair portions, said base having an upwardly bent portion in alignment with and abutting the end of the guard rail.

5. A railway track adjunct comprising a base, 30 a plurality of chairs forming an integral part thereof, each chair comprising two substantially upright converging portions, seats formed in said converging portions, a guard rail having a side wall with converging notches formed therein for 35 interlocking engagement with the chair portions, said base having at one end thereof an obliquely bent portion and said guard rail having an oblique portion in alignment and in abutting relationship therewith. 40
